UNITED STATES PATENT OFFICE.

WILLIAM B. CROWELL, OF NEW YORK, N. Y., ASSIGNOR TO ELEVATOR SUPPLIES COMPANY, INC., OF HOBOKEN, NEW JERSEY, A CORPORATION OF NEW JERSEY.

ELEVATOR AND INCLOSURE THEREFOR.

Application filed December 7, 1926. Serial No. 153,078.

This invention relates to elevators and elevator inclosures and has among its objects the provision of an improved type of elevator and an improved type of inclosure for elevators. These improvements in elevators and elevator inclosures, while capable of many different uses, are particularly designed for use in the modern office buildings, lofts, hotels, stores and other buildings having considerable traffic to and from the ground floor and also between the various floors.

In buildings of the types just referred to the problem of handling the traffic speedily and with a minimum of confusion is a serious one. As elevators are constructed at the present time it is necessary, when an elevator stops at a floor, for the persons desiring to board the elevator to wait until all persons within the elevator desiring to get off succeed in getting off, after pushing their way to the front of the car. This slows up the movement of the elevators and causes a great deal of annoyance to the passengers, particularly in cases where collisions occur between those trying to get in and those belatedly trying to get out.

To overcome this objection it is my intention to construct an elevator having an entrance separate from the exit so that the traffic in the two directions will be divided, thereby eliminating the present confusion. It is also my intention to provide the elevator inclosure with double means of access to each elevator at each floor in correspondence with the provisions made on the elevator itself.

Another object of the invention is to provide an elevator which will give the attendant or operator greater freedom from interference from passengers in his manipulation of the car and the various controlling devices.

A further object of the invention is to provide means for opening and closing both elevator doors or gates simultaneously and also both inclosure doors either simultaneously or selectively, thereby enabling the attendant to exercise control over the traffic in both directions in accordance with the necessities of the situation.

Other objects and advantages to be derived from the use of my novel mechanism lie in the specific construction and arrangement of the

parts and will become obvious as this description progresses.

With reference to the accompanying drawings, to which the description refers and wherein the preferred embodiment of the invention is illustrated, Figure 1 is a plan view partly in section of an elevator and an elevator inclosure built in accordance with my invention; Figure 2 is an elevation view along the corridor of a building containing a group of elevators provided with inclosures built in accordance with this invention; Figure 3 shows the preferred construction for the inclosure doors and the operating means therefor; Figure 4 shows the parts of Figure 3 in the position they assume when the doors are open; and Figure 5 is a view from the interior of the car and showing the construction of the elevator gates.

Referring to Figure 1, reference character 1 designates an elevator provided with openings as shown at 2 and 3, each of which openings is adapted to be closed by means of gates 4 and 5, shown best in Figure 5 and occupying the position indicated by dash lines in Figure 1.

Reference character 6 is used to indicate generally the inclosure walls which are provided with openings, as indicated at 7 and 8, the opening 7 being approximately opposite the opening 2 of the elevator and substantially equal thereto in size, and the opening 8 corresponding similarly to the opening 3 in the elevator. The opening 7 is provided with a door 9 and the opening 8 with a door 10, these doors being preferably of the horizontally sliding type. Furthermore, these doors in the preferred form of the invention are so arranged that they may slide toward one another while opening, each door having its own path of movement so that the doors when moved away from the openings will assume the positions indicated in dash lines in Figure 1 and shown also in Figure 4. The gates 4 and 5 on the elevator are also adapted for movement toward the center of the car when it is desired to provide for the entrance and exit of the passengers and for this purpose it has been found most suitable to provide gates of the collapsible type, the preferred construction being as shown in Figure 5,

where the gates are shown as being constructed of a series of vertical rods interconnected by lazy-tongs. Such a construction for a gate is not new and hence, by itself, 5 forms no part of the present invention.

The inclosure doors 9 and 10 are preferably non-collapsible in structure and are also preferably operated simultaneously by means of a single prime mover or actuating device. 10 While in the simplest form it is necessary to provide only manual control of the doors, it is nevertheless preferable to provide for power operation and in the preferred embodiment of this invention I have shown the 15 doors controlled by means of a fluid pressure engine indicated generally by reference character 25 in Figures 3 and 4. This engine 25 may be of any of the well-known types suitable for use in such a connection, such as, for 20 example, the well-known pneumatic engine similar to that shown in patent to Braden & Smalley #700,404, granted July 14, 1902. The door actuating mechanism 25 shown in Figures 3 and 4 is similar in most respects to 25 this disclosed in the said Braden & Smalley patent, but includes as an additional element a cushioning or dashpot mechanism 70 corresponding in substance to that shown in the Rowntree Patent No. 619,350 granted February 14th, 1899, and corresponding in form to that disclosed and claimed in the copending application of Harold W. Shonnard for 30 improvements in an adjustable door operator, filed March 8, 1926, Serial No. 93,086. This 35 door operating engine per se forms no part of the present invention, but in view of the novel door mechanism of this invention it has been necessary to devise novel means for transmitting the motion of the door engine to the doors 9 and 10. Such a novel mechanism is shown in Figures 3 and 4 and comprises a pair of rocker arms 26 and 27 mounted substantially vertically and connected to the doors 9 and 10 respectively, as shown at 40 45 and 29. Rocker arm 26 is pivotally fixed to the inclosure wall as at 30, and arm 27 is similarly pivotally fixed to the inclosure wall as indicated at 31. The two arms 26 and 27 are joined by means of a horizontally disposed cross-link 32 pivoted to rod 26 as shown at 33, and to rod 27 as shown at 34. This 50 55 cross-link 32 is adapted for movement with the cross-head 35 of the pneumatic engine 25, suitable connection for this purpose being indicated at 36.

With such an arrangement it will be apparent that the application of motive power, such as compressed air, to the piston of engine 25 will cause the latter to move, for example to the right in Figure 3, which movement of the piston will be transmitted in the conventional way to the cross-head 35 and thence to cross-bar 36. The movement of cross-bar 36 to the right thus produced will rock arm 26 in 60 65 counter-clockwise direction about its pivot

30, thus causing door 9 to move away from the opening 7. The same movement of cross-bar 36 will rock arm 27 in a clockwise direction about its pivot 31 and cause corresponding movement of door 10 to the left, and into 70 the open position shown in Figure 4 and indicated in dash lines in Figure 1.

When it is desired to again close the openings 7 and 8 the engine 25 will be reversed, either by the exhaust of pressure fluid therefrom or by the admission of pressure fluid to the opposite side of the piston, or by a combination of both of these operations. In any event the result produced will be a return movement of cross-head 35 to the left, as 80 shown in Figures 3 and 4, and thru the instrumentality of the connecting links and rocker arms previously described, doors 9 and 10 will again assume closed positions.

It is to be understood that the door operating engine 25 may be actuated in any suitable manner, such as by the provision of a valve actuating handle or pedal within reach of the elevator attendant, or if desired, the operation of the door engine may be made automatic upon the arrival of the elevator at the floor level. This latter operation may be produced by providing an electric circuit for the valve 37 or other device used to start the motor 25 in operation and by having such 90 circuit controlled thru the elevator controller indicated at 12. (Fig. 1.)

It is my purpose to provide means whereby the operator standing in a position opposite the elevator controller 12 may open both 100 the gates 4 and 5 and the doors 9 and 10 simultaneously by a single motion on his part. Such operation may be obtained by providing gates 4 and 5 with operating mechanism duplicating that shown for operating doors 105 9 and 10, and described hereinabove. Because such mechanism would duplicate that shown in Figures 3 and 4 and fully described above, further illustration is considered unnecessary; but assuming that 110 such a device is employed for the operation of gates 4 and 5, the valve 37 controlling the actuation of motor 25 and the corresponding valve controlling the actuation 115 of the corresponding motor for the elevator gates 4 and 5 can both be controlled by means of the electric circuit closeable thru manipulation of the attendant's control lever 12, as explained above.

A more common, and in fact the preferable 120 means for effecting simultaneous operation of both motors is illustrated in the drawing and comprises in part a pedal 40 or other operator controlled device within access of the operator and adapted to actuate both motors 125 by means of mechanical connections, first with the valve of the gate motor and secondly with the valve 37 of the door motor 25. The mechanical connections for the actuation of the valve 37 are shown in part in Figures 3 130

and 4 and consist of a link mechanism 41 connecting with the valve 37, as indicated at 42. As shown in Figures 3 and 4 a spring 43 is provided for maintaining valve 37 in the inoperative (that is, door closed) position; the link mechanism 41 serving to operate the valve against the force of spring 43 upon motion being imparted to the rocker arm 44 at the end of the link mechanism 41.

Such motion can be imparted to the rocker arm 44 by any suitable actuator mounted on and movable relatively to the elevator cage and into operative relation to rocker arm 44. A suitable device for this purpose is indicated at 45, which represent what is commonly known as a cam or shoe which may be projected into engagement with rocker arm 44 upon arrival of the elevator 1 at the landing, the projection of the cam being effected by pressure on the foot pedal 40 in the manner clearly illustrated and explained in patent to Bassett #1,601,841, granted Oct. 5, 1926, and in patent to Randall No. 1,347,711 granted July 27, 1920. Referring to Figure 5 of the drawings accompanying this specification such a suitable mechanism as applied to the shoe or cam 45 would comprise preferably a bracket 75, rigidly fastened to the roof of the car, on which the cam 45 may be made transversely movable through the provision of suitable links such as 76, to which may be connected at the outer end thereof a suitable vertically disposed actuating rod 77 extending downwardly to a point preferably beneath the floor of the elevator, at which point actuating means may be provided in the form of a bell crank 78, a horizontally disposed rod 79, and a second bell crank 80 having one end operatively connected with the rod attached to the operators foot pedal 40. With such an arrangement it is obvious that when the pedal 40 is depressed against the normal tendency of spring 81 such depression and consequent movement of the bell crank 80 and rod 79 will cause a corresponding movement of the vertically disposed rod 77 and a corresponding outward projection of the cam 45, thereby imparting motion to the valve operating links 44 and 41. Inasmuch as the projection of cam 45 may be accomplished in a variety of other ways and thru any suitable mechanical link motion, further explanation of this particular feature of the operation is believed unnecessary.

It is to be understood of course that the same means which produces the projection of cam 45 may also produce actuation of the valve controlling the motor mechanism for opening and closing gates 4 and 5 of the elevator. With such an arrangement the operator of the elevator would initiate the operation of both sets of doors simultaneously and by a single motion on his part.

Means are provided, as illustrated in Figure 5, to permit manual opening of gates 4

and 5 simultaneously in the event of failure of, or omission to supply, power operation for these gates. Such manual control preferably comprises a pair of flexible cables or ropes, as indicated at 13 and 14, attached to the vertical bars of the gates 4 and 5 respectively, as indicated, and converging at 15, where they are brought together to form a single rope or chain, which can be grasped by the operator. With such an arrangement it is possible for the operator to effect opening movement of both gates simultaneously by exerting a pull on the single operating member 16 and then locking the gates open by use of the catch shown at 17.

To assist in the closing movement of the gates 4 and 5 the gates are shown as provided with a sloping guideway both at top and bottom, as indicated in Figure 5, so that their own weight, when permitted to act, aids in returning them to closed position.

As shown at Figure 1 a barrier 39 is provided in the elevator 1 to assure the operator or attendant against interference from occupants of the car. This barrier may take any form deemed suitable in the particular case and it is to be understood that the form shown in Figure 1 is merely by way of illustration.

The appearance of a bank of elevators constructed in accordance with this invention is substantially as shown in Figure 2, where the sets of doors for three elevators are illustrated. With such an arrangement persons desiring to board an elevator station themselves opposite one of the entrance doors and out of the line of the exit doors, thereby leaving free passage from the elevator for passengers getting off. Preferably some designation will be placed on or near the entrance doors to distinguish them from the exit doors. As shown in Figure 2 this is done by placing the elevator signals over the entrance doors and by leaving the exit doors unmarked on the corridor side.

As illustrated in Figures 3 and 4, the doors 9 and 10 operate simultaneously thru the instrumentality of the rocker arms 26 and 27. Means are provided, however, for permitting selective operation of doors 9 and 10; and as shown in Figures 3 and 4 such means comprise a detachable pivot connection as shown at 50 between arm 26 and arm 51, and a similar detachable pivot connection 52 normally joining arm 27 with link 53. With this provision it is possible, for example, to have the operation of motor 25 produce opening and closing of door 10 without any movement of door 9, it being necessary merely to remove the pivot pin 50 from its connection with arm 26. Such selective operation is a desirable feature when the traffic in the building is light and the passengers getting in or out are few.

While I have shown and described the preferred construction of the parts involved in

my invention it is obvious that persons skilled in the art may utilize other constructions, combinations and arrangements of the parts and I therefore do not limit the invention to the specific construction shown but only by the scope of the appended claims.

I claim:

1. A four-walled elevator inclosure extending past a plurality of landings and provided with a pair of passageways in one of its walls at each landing, in combination with an elevator cage in said inclosure also provided with a pair of passageways in the corresponding wall.
15. 2. A four-walled elevator inclosure extending past a plurality of landings and provided with a pair of passageways in one of its walls at each landing, in combination with an elevator cage in said inclosure also provided with a pair of passageways in the corresponding wall, gates normally preventing passage of persons thru said passageways, a controller in said cage for causing the cage to stop opposite said landings, and means controlled from said cage for opening the gates at a landing opposite which said cage has stopped.
20. 3. Apparatus as in claim 2 wherein the gates at each landing are horizontally slideable along adjacent paths.
25. 4. Apparatus as in claim 2 wherein the gates at each landing are horizontally slideable along adjacent paths, and a single actuating engine causes simultaneous movement of both gates toward each other and along their respective paths.
30. 5. Apparatus as in claim 2 wherein the gates on the elevator cage are disposed in the same plane and are collapsible.
35. 6. Apparatus as in claim 2 wherein the gates on the elevator cage are disposed in the same plane and are collapsible toward a central point substantially midway of the cage wall.
40. 7. An elevator cage having one wall equipped with gates collapsible toward a central point substantially midway of the cage wall, in combination with an inclosure for said cage equipped with a pair of doors adjacent said gates, and means for simultaneously opening both said doors from with-

in said elevator cage, whereby ingress to and egress from said elevator cage is provided at two distinct locations at the same time.

8. An elevator cage having one wall equipped with collapsible gates, said gates normally preventing passage into or out of said cage, in combination with an inclosure for said cage and a pair of doors in the wall of said inclosure nearest said cage gates, said doors normally closing distinct passageways in said wall.

9. Apparatus as in claim 8 wherein a fluid pressure operated motor is provided for actuating said inclosure doors.

10. Apparatus as in claim 8 wherein cushioning means are provided for retarding the final movement of said inclosure doors in either direction of their movement.

11. Apparatus as in claim 8 wherein said collapsible gates, upon collapsing, clear two distinct passageways in said cage wall.

12. Apparatus as in claim 8 wherein means are provided for withdrawing said collapsible gates from two distinct passageways in said wall simultaneously, and means associated with said last named means are provided for positively restraining said gates in the withdrawn position.

13. Apparatus as in claim 8 wherein is also provided a door operating motor mounted on said inclosure wall and disposed above said pair of doors, and a pair of actuating connections from said motor to said doors.

14. Means for providing access to an elevator inclosure comprising a pair of horizontal slideable doors in one wall of said inclosure, a fixed panel in said wall between the passageways normally closed by said doors, means for simultaneously clearing both passageways comprising a door operating mechanism and connections from said mechanism to said doors whereby said doors are caused to slide toward said fixed panel, and means for rendering said last-named means operative to move said doors selectively rather than simultaneously.

Signed at Hoboken, N. J., this 3rd day of December, 1926.

WILLIAM B. CROWELL.
